UNITED STATES PATENT OFFICE.

JOSEPH H. McCLELLAND, OF WAYNE, NEW JERSEY.

BUNG-HOLE STOPPER OR SEAL FOR METALLIC KEGS.

SPECIFICATION forming part of Letters Patent No. 683,182, dated September 24, 1901.

Application filed April 24, 1901. Serial No. 57,426. (No model.)

To all whom it may concern:

Be it known that I, JOSEPH H. McCLELLAND, a citizen of the United States, residing at Wayne, in Wayne township, in the county 5 of Passaic and State of New Jersey, have invented certain new and useful Improvements in Bung-Hole Stoppers or Seals for Metallic Kegs, of which the following is a specification, reference being had therein to the accompanying drawings.

In metallic kegs or casks used for holding and transporting powder or other substances various methods have been devised for closing and sealing the bung-hole in the head of 15 the cask. Plates provided with an opening somewhat smaller than the bung-hole have been secured to the head of the barrel by turning the edge of the bung-hole over the edge of the hole in the plate to secure the 20 plate to the head of the keg, and the edge of the said plate, on three sides thereof, has been turned over to form a slide for a sheet of metal or shutter, which is pushed into the same, and the fourth side of said plate, being 25 made longer than the shutter, is adapted to be bent over the end of the shutter to secure the shutter over the bung-hole. That method of closing the keg has been varied by having two of the edges of the shutter turned over, 30 so as to form a slide adapted to receive and pass around two of the edges of the plate, which is secured to the head of the keg, and the shutter is secured to the plate on the head of the keg by turning the ends of said plate 35 over the other two ends of the shutter. In both of the methods above mentioned considerable time, labor, and material are employed; and the objects of my invention are to accomplish the same purposes with less 40 time, labor, and material and to provide a more perfect bung for the bung-hole in the head of a metallic keg and one that will not project above the head of the barrel so as to present an object for contact with obstacles 45 in the handling of the keg and which will at the same time prevent the leak or escape of powder or other explosive materials from the keg. I attain these objects by means of the barrel-head, bung-hole, and stopper or seal, 50 arranged as hereinafter described and shown, and illustrated in the accompanying drawings, which are made part hereof and in which

similar parts are similarly indicated in the drawings.

Figure 1 is a top plan view of my bung secured in the bung-hole of a barrel-head. Fig. 2 is a vertical transverse section of the same on line *x x*, Fig. 1, inverted; and Fig. 3 is a top plan view of the bung.

Like numerals of reference indicate like 60 parts throughout the drawings.

4 is a metallic bung which is formed like a shallow dish and provided with an annular flange 5.

6 is the head of a cask, keg, or barrel, also 65 metallic, through which is a circular opening or bung-hole, around the edge of which bung-hole is an annular depressed portion of the head 6, adapted to receive the annular flange 5 of the bung, which is formed to fit 70 into said annular depressed portion.

8, 9, and 10 are tongues forming an integral part of the head 6 and adapted to be raised while the bung 4 is placed in the bung-hole, the lower depressed portion of the 75 bung passing through and fitting snugly in said bung-hole and its annular flange 5 resting in the annular depressed portion of the head 6, which surrounds the bung-hole. The tongues are adapted to be hammered 80 down over the annular flange of the bung. The tongues 8, 9, and 10 when raised leave openings in the head 6, which are covered by the annular flange 5 of the bung. The depressed portion 11 of the bung, which is shown 85 inverted in Fig. 2, fits snugly into the circular opening or bung-hole in the head 6. The vessel is thus tightly sealed, and the prevention of the leakage or escape of the contents is insured.

While my invention relates particularly to metallic casks for holding and transporting explosive substances, it is obvious that it may be employed also for other purposes and that minor changes may be made and alterations 95 in the construction without materially departing from the essential principles or scope of my invention. For instance, a can for carrying milk or other liquids might be provided with my invention, and a wooden cask 100 could be fitted with a metallic rim or bushing around the bung-hole, having a depressed portion provided with tongues adapted to retain a bung, as above described.

When it is desired to remove my bung, one or more of the tongues are pried upwardly. The dished portion of my bung may be shallow or otherwise, as desired. The bung-hole 5 in the top or end of a metallic cask or barrel and the depressed annular portion around the bung-hole, as well as the tongues which are cut integral with the top or end of the vessel, are all made by me in one operation 10 to by a combination-die, which presses the material, cuts out the bung-hole, and cuts the tongues, forcing one of them downwardly into a vertical position and the others downwardly at an angle. It is obvious that the 15 flange of the bung may be inserted readily under two of the tongues and will rest upon the depressed surface surrounding the bung-hole, when the three tongues may be hammered down over the flange of the bung, 20 tightly sealing the keg or other vessel.

With this description of my invention, what I claim is—

1. In a metallic vessel, a closing device 25 consisting of the head having a centrally-depressed portion, provided with an opening or bung-hole, which is formed by cutting a piece out of said depressed portion, leaving a flat annular edge around the bung-hole at the bottom of the shoulders which are formed by 30 depressing the central portion of the head, and tongues cut out of, and integral with, the said flat annular depressed portion surrounding the bung-hole, and raised upwardly to permit the insertion under the same of the 35 edge of a metallic bung, in combination with a metallic bung formed like a shallow dish having a sunken portion adapted to fit snugly

into the said bung-hole, and provided with an annular flange adapted to rest on the annular flat depressed portion of the head which 40 surrounds the bung-hole, to cover the openings made by raising said tongues, and to be held there in place by the lowering of said tongues down over the annular flange of the bung below the level of the top of the vessel, 45 substantially as set forth.

2. In a vessel for explosives; a metallic head; provided with a circular opening, and an annular depressed portion surrounding said opening, two or more tongues cut out of, and 50 forming an integral part of, said annular depressed portion surrounding said opening, in combination with a metallic bung having a substantially vertical annular wall around the 55 bottom thereof, and adapted to fit tightly down through, and into, said circular opening in the head, said bung having an outwardly-projecting annular flat flange at the top thereof adapted to pass under the elevated 60 tongues in the annular flat depressed portion of the head, and to rest upon said depressed portion, and to cover the holes in said portion, said tongues being adapted to be lowered over the outwardly-projecting flange of said 65 bung, for tightly sealing the vessel, substantially as set forth.

In testimony whereof I affix my signature in presence of two witnesses.

JOSEPH H. McCLELLAND.
